UNITED STATES PATENT OFFICE.

ANNA K. MAY, OF PHILADELPHIA, PENNSYLVANIA, ASSIGNOR TO McCALLUM & McCALLUM, OF SAME PLACE.

DESIGN FOR CARPET.

SPECIFICATION forming part of Design No. 25,294, dated March 24, 1896.

Application filed February 24, 1896. Serial No. 580,525. Term of patent 31 years.

To all whom it may concern:

Be it known that I, ANNA K. MAY, a citizen of the United States, residing at the city of Philadelphia, in the county of Philadelphia and State of Pennsylvania, have invented and produced a new and original Design for a Carpet or other Fabric, of which the following, taken in connection with the accompanying drawing, is a specification.

- 5 ○ The pattern or ornamentation represented in the accompanying drawing constitutes my design and presents the appearance which distinguishes it in the eye of the observer from other designs.
- 5 ○ In the drawing, A is the body, B the border, and A and B the carpet.

This design may be wrought upon the face of Brussels, Wilton, velvet and other carpets, and of course may be made to appear in a

- variety of different colors and combinations of colors.

The leading or characteristic feature of my design may be said to be the ornamental thing a, displayed upon a background b and associated with the ornamental figures c. The 25 figures or ornaments a and c are disposed linearly or substantially so.

What I claim as new, and desire to secure by Letters Patent, is—

1. In the design for a carpet the body A, 30 substantially as shown.
2. In a design for a carpet the border B, substantially as shown.
3. The design for a carpet consisting of the body A, and the border B, substantially as 35 shown.

In testimony whereof I have hereunto signed my name in the presence of two witnesses.

ANNA K. MAY.
